ELECTRIC LIGHTING DEVICE

Harry A. Douglas, Bronson, Mich., assignor to
 Kingston Products Corporation, a corporation
 of Indiana

Application March 2, 1936, Serial No. 66,652

5 Claims. (Cl. 240—41)

My invention relates to electric lighting devices, and more particularly to electric lamp units comprising an incandescent electric lamp mounted in a reflector, as for example, in an automobile headlight, and the principal object of my invention is to provide a new and improved lighting device and unit of this type.

In the drawings accompanying this specification, and forming part of this application, I have shown, for purposes of illustration, one form which my invention may assume. In these drawings:

Figure 1 is a vertical sectional view, certain parts being fragmentarily shown, of one embodiment of my invention.

Figure 2 is a front elevation of a detail.

Figure 3 is a side elevation of parts of a holding means or socket unit, forming part of the embodiment of Figure 1, before they are completely assembled.

Figure 4 is a front elevation of the holding means or socket unit, forming part of the embodiment shown in Figure 1.

Figure 5 is a side elevation of the holding means shown in Figure 4.

Figure 6 is a fragmentary sectional view taken on the line 6—6 of Figure 4.

Figure 7 is a front elevation of the mounting with the holding means, shown in Figures 4 and 5, assembled therewith.

Figure 8 is a side elevation of the parts shown in Figure 7.

Figure 9 is a section taken along the line 9—9 of Figure 10, looking in the direction of the arrows.

Figure 10 is a side elevation of the incandescent electric lamp used in the embodiment of Figure 1, the bulb of the lamp being fragmentarily shown, and

Figure 11 is a perspective view of the rear of the mounting.

Referring to Figure 1, the embodiment of my invention here illustrated is shown as including an incandescent electric lamp 20, adapted to be suitably connected to a mounting 21, the mounting being in this instance a reflector fragmentarily shown. The lamp 20 is provided with a base 22, which in this instance includes laterally extending positioning means 23. The base includes a shell 25 and the laterally extending portion of the base comprises a collar 26 surrounding the shell 25 and a radially extending flange 27 on the collar. The collar 26 may be fastened to the shell 25 in any suitable manner, as by soldering 28 (see Figure 9). As may be seen in Figure 9,

the flange 27 is, in this instance, circular in outline. The flange 27 is provided with, desirably three, axially extending projections 29 formed by making depressions 30 in the opposite face of the flange 27. The base is further provided, in this instance, with two lateral projections in the form of cylindrical pins 31, 32, for a purpose which will appear. The pins 31, 32 are circumferentially spaced less than 180°, as may be seen in Figure 9, and are in a plane spaced from the plane of the flange 27. The collar 26 is provided with slots 33, 34, to enable the collar to be slipped over the pins 31, 32.

The reflector 21 is here shown as being provided with a cup-shaped extension 35 including a rearwardly extending cylindrical portion 36, the inner periphery of which is shown as slightly spaced from the radially outer periphery of the lamp flange 27, but which may gage this outer margin, that is, snugly fit it. The cup-shaped extension 35 also includes an apertured plane end or bottom 37, seen most clearly in Figure 11. The bottom 37 is provided with a central aperture 38, sufficiently large to permit easy passage of the shell 25 of the lamp base. Extending radially outwardly from the central aperture 38 are three generally rectangular circumferentially spaced recesses 39, thereby leaving three generally segmental flanges 40. When the flange 27 is in the position shown in Figure 1, the three axially extending projections 29 abut respectively the front surfaces of the three segmental flanges 40. By front and rear are meant parts presented toward or away from the light producing source of the lamp 20.

In order to hold the lamp 20 assembled with the reflector 21 in the position shown in Figure 1, a holding means or socket unit 41 is provided. This holding means 41 comprises a shell 42, desirably of generally cylindrical form, which may be seamless, and desirably formed of sheet metal. The holding means also includes a biasing means 43, fixed to the shell 42, the biasing means in this instance comprising a ring 44 of sheet metal, provided with circumferentially spaced portions, here three in number, extending in a generally radial direction outwardly from the ring 44, and looped or bent radially inwardly so as to form spring loops 45. The free ends of the spring loops 45 are detachably connected to the reflector by bayonet connections. To this end, the reflector is here shown as provided with three axially rearwardly extending projections 46 of generally plane form. These projections may be formed from metal, left in forming the circumferentially

spaced recesses 39. The projections 46 are here shown as having straight axially extending margins 85, 86, the distance between which is less than the width of the recesses 39. Each of the 5 projections 46 is provided with a slot 47 extending from one axial edge, 85, thereof transversely into the projection a predetermined distance. The front margins 48 of the slots 47 are desirably formed by the junction between the rear face 10 of the end flange 37 of the tubular projection 35 on the reflector and the radially outer end of each recess 39. In this instance the margins 48 are in the planes of the radially outer faces of the projections 46. The width of the slots 47 is desirably approximately the same as the thickness 15 of the free ends of the spring loops 45.

The spring loops 45 are provided near their free ends with transverse slots 49 extending from one margin thereof a predetermined distance. 20 The width of these slots 49 is approximately the same as the thickness of the rearward projections 46 on the reflector. At the margins of the free ends of the spring loops 45, opposite the margins into which the slots 49 extend, is provided a front- 25 wardly extending shoulder 50, here shown as formed by bending frontwardly a portion of the radially extending margin of each spring loop (see Figure 6). The shoulders 50 serve to engage margins 51 of the recesses 39 and prevent rotation of the holding means 41 when the holding 30 means is mounted on the reflector. The spring loops 45 and the projections 46 may be unequally spaced circumferentially if desired.

The ring portion 44 of the biasing means has 35 a central aperture 52 of approximately the same diameter as the outside diameter of the shell 42, and extending radially inwardly from the aperture 52 are, in this instance, three circumferentially spaced projections 53, 54, 55, of unequal 40 circumferential extent, adapted to be seated in the bottoms of complementary axially extending recesses 56, 57, 58 at the rear end of the shell 42.

The holding means 41 serves also to carry an insulating contact carrier 59, the outside diameter 45 of which is substantially equal to the inside diameter of the shell 42 and has radially outwardly extending projections 60, 61, 62, desirably complementary to the three axially extending recesses 56, 57, 58 in the rear end of the shell 42, so that the contact carrier 59 may be assembled 50 with the shell in only one relative rotative relation. When the contact carrier 59 is assembled with the shell 42 its front face abuts the rear face of the ring 44. In order to hold the contact carrier 59 to the shell, rearwardly extending fingers 55 63 are provided on the shell 42, which may be clinched radially inwardly over the rear face of the insulating contact carrier 59.

The contact carrier 59 is adapted to carry 60 contacts 64, 65, these contacts being desirably formed as enlarged heads on shanks fitted over and swedged to the ends of conductors 66, 67 respectively. The conductors 66, 67 are disposed in sleeves, one of which, 68, is visible in Figure 1, 65 each sleeve being slidable within a bushing 69, which is fixedly mounted, in any suitable manner, as by beading, through the insulating carrier. Each sleeve is surrounded by a spring 70 between the bushings 69 and a flange 71, each 70 sleeve abutting the respective contacts 64, 65.

The contacts 64, 65 are adapted to make contact respectively with a pair of contacts 72, 73 on the base of the incandescent lamp 20. One of the contacts (73) on the base of the lamp 20 is shown 75 in Figure 1 as in contact with the spring pressed

contact 65, the cooperating contacts 72, 64 being directly behind the contacts 73, 65. The provision of a plurality of contacts on the lamp base enables the use of a multiple filament lamp, the lamp being here shown as provided with two 5 filaments 74, 75, one of which, 74, may desirably have its lighting center at some predetermined point with respect to the reflector, as for example at the focus, and the other of which, 75, may be displaced from the filament 74, and may be used 10 for providing dim light or so-called tilted light. The filaments 74, 75 have their terminals connected in a well known manner to the lamp base 22 and to the contacts 72, 73 on the lamp base. The passage of current to either one or 15 both of the filaments 74, 75 may be controlled in any suitable manner, by switching means (not shown) interposed in the conductors 66, 67.

The shell 42 of the holding means 41 is provided with bayonet slots 76, 77, each slot having 20 an axially extending entrance portion 78, connected by a slanting portion 79, proceeding in partly a circumferential and partly an axial direction to a generally rounded seat portion 80. The bottom 84 of the seat portion 80 is disposed 25 frontwardly of the junction 81 between the frontward margins of the slanting portion 79 and the seat portion 80, so that the approach to the shoulder formed by the junction 81 is by cam surfaces 82, 83.

When the lamp 20 is in assembled position with the reflector 21 and holding means 41, as shown in Figure 1, the pins 31, 32, are seated on the bottoms 84 of the seat portions of the bayonet slots 76, 77. Accordingly the bayonet 35 slots 76, 77 are disposed circumferentially in the shell 42, complementarily to the pins 31, 32.

In assembling the unitary holding means 41 the biasing means 43 is first assembled with the shell 42 by slipping it over the rear end of the 40 shell with the projections 53, 54, 55 in registry with the axially extending recesses 56, 57, 58 at the rear end of the shell. The contact carrier 59, with the contacts carried thereby, is then assembled with the assembled shell 42 and biasing means 43 by bringing the radially extending projections 60, 61, 62 into registry with the axially extending recesses 56, 57, 58 in the shell 42 and then clinching the fingers 63 over the rear end of the insulating carrier 59. The holding means 41 then has the appearance as illustrated in Figures 4 and 5.

In assembling the holding means 41 with the reflector 21, the free ends of the spring loops 45 are first brought up against the desired rear 55 faces of the segmental flanges 40 respectively and the holding means 41 is then turned in a clockwise direction, as viewed from the rear of the reflector 21, whereupon the margins of the slots 49 in the spring loops 45 will embrace the unslotted portions of the rearward projections 46 on the reflector and the margins of the slots 47 in the rearward projections 46 will embrace the unslotted portions of the spring loops 45. Meanwhile, the shoulders 50 bear against the 60 rear faces of the segmental flanges 40, and, as rotation of the holding means 41 is continued, the trailing margins of these shoulders 50 will snap frontwardly off of the margins 51 of the recesses 39. When the parts have reached this position 65 the ends of the slots 47 and 49 are desirably in engagement, so that further clockwise movement of the holding means 41 is prevented, and counter clockwise movement is prevented by abutment of the shoulders 50 with the margins 70 75 70 75

51. The assembled reflector 21 and holding means 41 appear as in Figures 7 and 8.

When it is desired to assemble the lamp 20 with the assembled reflector 21 and holding means 41, the shell portion 25 of the base of the lamp 20 is inserted through the central aperture 38 in the reflector and the pins 31, 32 are brought into registry with the axially extending entrance portions 78 of the bayonet slots 16, 17 in the shell 42, axial movement of the lamp toward the reflector being continued, against the bias of the contacts 64, 65, and of the spring loops 45, until the axially extending projections 29 abut the front faces of the flanges 40. At this time the pins 31, 32 are in a position to engage the cam surfaces 82 of the bayonet slots 16, 17, upon rotation of the lamp 20 in a clockwise direction as viewed from the front of the reflector 21. Upon such rotation of the lamp 20, cooperation between the pins 31, 32 and the cam surfaces 82 causes the shell 42 to be moved frontwardly against the bias of the spring loops 45, until the pins 31, 32 pass the shoulders 81, whereupon the bottoms 84 of the seat portions 25 of the bayonet slots 16, 17 are drawn against the front sides of the pins 31, 32, by the bias of springs 45, and the projections 29 on the lamp base flange are consequently pressed against the front faces of the reflector flanges 40, the parts being then in the position shown in Figure 1.

It will be evident that since the flange 27 is accurately pre-positioned with respect to its distance from the filaments 74, 75 and the direction 35 of the plane of the flange is pre-positioned with respect to the axis of the lamp, and, furthermore, since, the pins 31, 32, in conjunction with the bayonet slots 16, 17, permit assembly of the lamp 20 with the reflector 21, in only one relative rotative relation, the filaments 74, 75 will assume the desired predetermined position when the parts are assembled as in Figure 1.

Removal of the lamp 20 may be effected by simply rotating it in a counter clockwise direction, the pins 31, 32, in cooperation with the cam surfaces 83 of the bayonet slots 16, 17, causing the shell 42 to be pulled frontwardly until the pins ride over the shoulders 81, the cam surfaces 82 thereafter riding along the pins 31, 32, the shell 42 being permitted to move rearwardly as the pins 31, 32 move circumferentially. When the pins 31, 32 reach the axially extending portions 78 of the bayonet slots 16, 17, the lamp may be withdrawn by axial movement 55 away from the reflector.

The holding means 41 may be removed from the reflector 21 by pressing the shoulders 50 rearwardly enough to permit releasing rotation of the holding means. Rearward movement of the shoulders 50, as distinguished from bodily rearward movement of the entire free ends of the spring loops 45 is possible since the axial margins 85 of the projections 46 are spaced from the margins 51 of the recesses 39, so that the free ends of the loops may flex about the frontward ends of the margins 85.

From the foregoing it will be apparent to those skilled in the art that the illustrated embodiment of my invention provides a new and improved electric lighting device and unit, readily and conveniently constructed and assembled, and accordingly, accomplishes the principal object of my invention. On the other hand, it also will be obvious to those skilled in the art that the 75 illustrated embodiment of my invention may be

variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. In combination: an incandescent electric lamp having a base; a reflector; said base having a lateral extension abutting said reflector at the front thereof; means for engaging said base; biasing means, unitary with said engaging means, for biasing said engaging means to cause said lateral extension to abut said reflector; said 10 biasing means including a resilient member serving to support said engaging means from said reflector; and said reflector and said resilient member being so constructed and arranged that they make bayonet connection with each other 15 seated by rotation of said biasing means about its axis relative to said reflector.

2. In combination: an incandescent electric lamp having a base including a lateral extension and including also a portion, separate from said lateral extension, having a surface extending transversely to the axis of said lamp; a mounting member; means constructed and arranged to engage said surface and thereby pull said lateral extension toward said mounting member; auxiliary means, unitary with said engaging means, constructed and arranged to bias said engaging means to cause said lateral extension to abut said mounting; contact means, carried by said 25 auxiliary means, constructed and arranged to cooperate with said lamp; said auxiliary means including a resilient member; and said resilient member and said mounting member including connection means so constructed and arranged that said resilient member is detachably mounted on said mounting member and said resilient member alone serves to support said auxiliary 30 means from said mounting member.

3. In combination: an incandescent electric lamp having a base including a lateral extension and including also a portion, separate from said lateral extension, having a surface extending transversely to the axis of said lamp; a mounting member, abutted by said lateral extension at one side thereof, said surface being disposed at the other side of said mounting member; means for engaging said surface, said surface and said engaging means being so constructed and arranged that movement of said engaging means away from said other side of said mounting is adapted to move said base in the same direction; contact means, carried unitarily with said engaging means, constructed and arranged to cooperate with said lamp; and means for biasing said engaging means in said 45 direction thereby to cause said lateral extension 50 to be pressed against said mounting.

4. In combination: an incandescent electric lamp having a base including laterally extending means having portions defining a plane transverse to the axis of the lamp; a mounting member abutted by said laterally extending means thereby to definitely position said plane; an auxiliary mounting member; means for supporting said auxiliary mounting member from said 55 mounting member, so constructed and arranged that said auxiliary mounting member is movable relatively to said lamp, axially of said lamp, and is biased to a position away from the light source 60 of said lamp; said auxiliary mounting member 65

and said lamp including means for connecting said lamp to said auxiliary mounting member; said connecting means including a slot in said auxiliary mounting member, and a projection carried by said base constructed and arranged to cooperate with said slot; said slot and said projection being so constructed and arranged that rotation of said lamp causes said auxiliary mounting member to move toward the light source of said lamp thereby to press said laterally extending means against said mounting member.

5. In combination: a mounting having an aperture and having a plurality of circumferentially spaced recesses extending outwardly from said aperture; an incandescent electric lamp pro-

vided with a base having contact means; said base being disposed in said aperture and having a lateral extension constructed and arranged to abut said mounting; said mounting having integral circumferentially spaced projections disposed around said aperture at the ends of said recesses; said projections extending laterally from one side of said mounting; and means, carrying contact means cooperable with said contact means on said base, constructed and arranged to be detachably supported by said mounting projections and so as to press said lateral extension into abutment with said mounting.

HARRY A. DOUGLAS. 15
